UNITED STATES PATENT OFFICE.

CHARLES O. HEGGEM, OF MASSILLON, OHIO, ASSIGNOR TO RUSSELL & CO.,
OF SAME PLACE.

DESIGN FOR A STEAM-ENGINE CYLINDER.

SPECIFICATION forming part of Design No. 25,526, dated May 19, 1896.

Application filed March 2, 1895. Serial No. 540,386. Term of patent 7 years.

To all whom it may concern:

Be it known that I, CHARLES O. HEGGEM, a citizen of the United States, and a resident of Massillon, county of Stark, State of Ohio, 5 have invented and produced a new and useful Design for Steam-Engine Cylinders, of which the following is a full, clear, and exact description, reference being had to the accompanying drawing, making part of this specification.

The design relates to steam-engine cylinders and their extended parts, having the form and configuration shown in the accompanying drawing, wherein the design is represented in perspective.

The leading features of the design comprise

the approximately rectangular frame A, having a marginal flange or border and segmental extension B, the cylindrical part C, having a segmental extension D, converging arms E, 20 and the forward projected smaller cylindrical portion F.

What I claim is—

The design for steam-engine cylinders as shown and described. 25

In testimony whereof I have hereunto set my hand this 9th day of February, A. D. 1895.

CHARLES O. HEGGEM.
